(57) **CLAIM**

The ornamental design for a wireless food thermometer, as shown and described.

DESCRIPTION

FIG. 1 is a front perspective view of a wireless food thermometer, showing my new design;

FIG. 2 is an exploded rear perspective view thereof;

FIG. 3 is a front view thereof;

FIG. 4 is an exploded front view thereof;

FIG. 5 is an exploded rear view thereof;

FIG. 6 is an exploded left-side view thereof;

FIG. 7 is an exploded right-side view thereof;

FIG. 8 is a top view thereof; and,

FIG. 9 is a bottom view thereof.

The broken lines in the drawings illustrate the portions of the wireless food thermometer, which form no part of the claimed design.
